2,419,549

RADIO REFLECTING AND LOW DRAG
TOW TARGETJohn W. Griesinger, Dayton, Ohio, and Hymen
Goldstein, Fairlawn, N. J.

Application August 24, 1944, Serial No. 551,046

2 Claims. (Cl. 273—105.3)

(Granted under the act of March 3, 1883, as
amended April 30, 1928; 370 O. G. 757)

1

The invention described herein may be manufactured and used by or for Government for governmental purposes, without the payment to us of any royalty thereon.

This invention relates to tow targets, and more particularly to aerial trailers to be towed behind airplanes and used as radio reflecting targets.

One of the main objects of this invention is to provide a tow target which will produce efficient reflection of radar beams, comparable to an actual aircraft, and is especially adapted for use for anti-aircraft gun laying purposes and other radar applications.

Another object of this invention is to provide a tow target which comprises intersecting planes that can be compacted or folded together and also launched in the same manner as the ordinary tow target, such as the single plane target or the sleeve target, and which is furthermore equipped with tow cables so arranged that by the launching operation the intersecting planes will promptly unfold and assume operative spread-apart positions.

Another object of this invention is to provide a target which presents the same projected area as the present sleeve target having the same over-all dimensions, but which presents considerably less drag resistance than such sleeve target, thus providing a low drag target allowing higher towing speed.

A more particular object of this invention is to provide such a tow target comprising two intersecting flag-type strips of wire mesh material which will reflect radar waves efficiently and will also provide semi-rigidity and thereby a low drag resistance, and which strips are equipped with a bridle arrangement of towing cables for automatically spreading the planes during launching to assume a position normal to each other.

Other objects and advantages are attained with this invention, as will become apparent from the following description taken in connection with the accompanying drawings wherein this invention is shown in a preferred form of construction.

In the drawing:

Fig. 1 is a side elevational view of our radio reflecting tow target shown in its unfolded, operative position.

Fig. 2 is an end elevational view thereof.

Our invention comprises a plurality of connected planar bodies or flag-type strips of material adapted to reflect radar waves efficiently, in the same manner as an aircraft, and in the drawing this is shown as comprising two intersecting bodies or strips 5 and 6 which are mounted

2

to be foldable together; and the invention comprises towing means 7 connected in bridle arrangement to these bodies or strips so that during launching they will be automatically drawn into a spread-apart position with the strips placed normal to each other, as illustrated.

These bodies or strips 5 and 6 are readily constructed by the use of a pair of tubular metal members 9 and 10 which provide tow bars at the leading part of the body and are pivotally connected by a bolt 11 extending thru the central parts of said members. Each member has the mesh material 12 mounted thereon, which is of meshed wire or of such material as to efficiently reflect radar waves; and for the present purpose we preferably use cotton covered wire mesh material having its meshes so dimensioned that the distance between the companion wires of a mesh is a function of the radar wave length, the meshes being preferably spaced 16 to the inch, thereby assuring maximum reflection of radar waves. This material 12 has its forward end portion doubled over and secured in position by suitable stitching 13 to provide a broad hem or pocket 14 for receiving the bar therein, while the rear end of the body of material may be strengthened by hemming it and securing it by stitching 15. The central hem portion of the front hem 14 of body 5 is cut away to provide an opening 16 where the front part of body 6 intersects the same, and the exposed edges are preferably reinforced with cotton tape 16 secured thereover, as shown in Fig. 1.

One of the bars, and as shown herein the bar 9, is provided with stop lugs or retainers 17 thereon to limit the unfolding movement of bar 10 relative to bar 9, so that the tow bars in the unfolded position are spread apart and placed substantially normal to each other, while the stop lugs 17 enable the bars 9 and 10 along with their bodies of mesh material to be folded against each other into a flat position.

The tow cable means 7 in this invention is arranged and connected with the two bodies in a style which is herein termed and is known as bridle arrangement or bridle formation; and herein this cable means comprises a pair of cables 18 connected to a pair of eyes 19 provided adjacent the ends of bar 9, and extending to or made integral with a loop 20 at the forward end of the cable means. This cable means also comprises a pair of cables 21 which are connected to said pair of eyes 19 and extend therefrom slidably thru a pair of eyes 22 provided adjacent

the ends of bar 10, and thence continue to and are made integral with the front loop 20.

It should be noted that each of the cables 21 is slightly longer than either of the cables 18, by the length of cable 21' which extends between eye 19 and eye 22 when the target is unfolded, as shown in Fig. 2; so that the length of the slanting cable 18 which extends from eye 19 to loop 20 will equal the length of the slanting main part of cable 21 which extends from eye 22 to loop 20. In this manner of bridle arrangement of the tow cables, when the device is launched from the plane in its usual rolled-up position it will unroll and the cables will automatically draw the pivotally joined bars 9 and 10 and spread them apart into the operative or crossed position, whereby the planar bodies will be spread apart and placed normal to each other, in the position shown in the drawing.

One of the bars, the bar 9 as shown herein, is provided with a weight 23 at its outer end, so that this bar and the strip of mesh material extending flag-type therefrom will assume a substantially vertical position during operation, while the bar 10 with its flag-type strip of mesh material will assume a substantially horizontal position, as the tow target trails behind the traveling airplane.

This device is readily folded together by superposing the pair of flag-type strips and rolling them up from the rear or tail end, and the bridle lines are folded under the last roll to prevent entangling during launching, with the loop 20 left extending from the last roll. The target can then be readily launched from the airplane and thru the bridle arrangement of the cables the two strips will thereby automatically assume the unfolded operative position normal to each other, with the strip 5 vertical and the strip 6 horizontal, and loop 20 will be aligned with the central axis of the target while it is towed by the aircraft, thus producing a readily operable low drag tow target providing a highly efficient reflecting surface for radar beams.

We claim:

1. A tow target comprising two flag-type bodies including frame means pivotally connected to be foldable together, wire mesh material secured to said frame means and connected along

the longitudinal middle line providing intersecting bodies capable of reflecting radar waves, towing means including two pairs of cables, one pair being longer than the other, said cables being joined at the front ends and each pair having its rear ends connected to the outward parts of one of said frame means, the longer pair also extending slidably through means on the outward parts of the opposite frame means, whereby the bodies will be drawn apart from the folded position to a position normal to each other during launching, and means to limit the unfolding movement of the bodies when normal to each other.

2. A radio reflecting tow target comprising two flag-type bodies including a pair of front bars pivotally connected at the central points to enable folding the bodies together, wire mesh material secured at its leading edge on each bar and extending flag-type therefrom, said mesh material being joined along the longitudinal middle line to provide intersecting bodies and the meshes being spaced relatively closely for efficiently reflecting radar waves, towing means including a long pair and a short pair of cables joined into a loop at the front and each pair having the rear ends connected to the end parts of one of the bars, with the cables of the longer pair also extending slidably through means on the end parts of the other bar, stop means on the bars to limit their unfolding movement when normal to each other, thus providing a bridle arrangement to draw the bodies normal to each other during launching, and a weight on an end of one of said bars to position its body in a vertical plane during the towing operation.

JOHN W. GRIESINGER.
HYMEN GOLDSTEIN.
